EDWARD HOWARD, OF REDHILL, ENGLAND.

Letters Patent No. 70,721, dated November 12, 1867.

IMPROVEMENT IN THE MODE OF PREVENTING THE EXPLOSION OF LAMPS.

The Schedule referred to in these Letters Patent and making part of the same.

TO ALL WHOM IT MAY CONCERN:

Be it known that I, EDWARD HOWARD, a member of the Royal College of Physicians, of London, of Redhill, in the county of Surrey, England, have invented a new and improved Mode of Preventing the Explosion of Lamps used for consuming paraffine, camphine, belmontine, rock oil, crystal oil, or any other combustible carbonaceous oils or spirits; and I do hereby declare that the following is a full and exact description thereof, reference being had to the accompanying drawing, and to the letters of reference marked thereon.

The nature of my invention consists in preventing the explosion of lamps used for burning any of the aforesaid materials by absolutely preventing communication between the flame of the wick and the upper part of the chamber containing the oil or spirit to be consumed.

To enable others skilled in the art to make and use my invention, I will proceed to describe its construction and operation.

I construct my lamp in any of the forms in which paraffine lamps are commonly made. I then add a tube, A, made of tin or other insoluble material, of a size and shape to fit loosely over the wick, which I fit close to the under surface of the cap B. This tube A must be long enough to reach down to within about one-quarter of an inch from the bottom of the vase. Through this tube the wick passes into the vase. All communication between the outside of the lamp and the inside is thus prevented, except through the tube A and a groove (to admit air) in the collar of the burner C. All other openings are closed, and an explosion is impossible.

What I claim as my invention, and desire to secure by Letters Patent, is—

The application of the long tube A, before named, and the substitution for the usual openings of a groove in the collar of the vase C, so that by no opening can the flame of the lamp reach the gas in the vase.

EDWARD HOWARD.
